UNITED STATES PATENT OFFICE.

DANIEL WILLIAMSON, OF SUNBURY, PENNSYLVANIA, ASSIGNOR OF ONE-HALF TO JASPER SLAYMAKER, OF SAME PLACE.

ICE-CUTTER.

SPECIFICATION forming part of Letters Patent No. 395,100, dated December 25, 1888.

Application filed July 14, 1888. Serial No. 280,007. (No model.)

To all whom it may concern:

Be it known that I, DANIEL WILLIAMSON, of Sunbury, in the county of Northumberland and State of Pennsylvania, have invented a new and useful Improvement in Ice-Cutters, of which the following is a specification.

The object of my invention is to provide an ice-cutting machine which may be conveniently operated by hand for cutting grooves into the surface of ice upon rivers to facilitate its division into regular blocks preparatory to harvesting the same.

Figure 1 is a side elevation, partly in section; and Fig. 2 is a plan view.

In the drawings, X represents the main frame of the machine. In journals in the upper part of this frame there is mounted a shaft, O', provided with a crank-handle, P, by which power is transmitted to work the machine. From this point of application the power divides, part of it going to the cutting-chisel to work it and the other part going to the propelling devices for giving a slow progressive motion to the machine across the ice. For the latter purpose the shaft O' has rigidly attached to it a pinion or small gear-wheel, O, which meshes with a large gear-wheel, N, on a shaft, M', below, which latter shaft has also a rigidly-attached gear-wheel, M, which again meshes into a large gear-wheel, L, below. This wheel L is rigidly attached to a shaft, K', which latter is also provided on each side of the machine with a supporting and propelling-wheel, K, which propelling-wheels are formed with teeth or spurs that penetrate the ice and secure a hold thereupon for propelling the machine. This train of gears just described, it will be seen, causes a diminished motion to be transmitted from the crank-handle to slowly propel the machine over the ice. On the same shaft O' bearing the crank-handle there is rigidly attached a large gear-wheel, A, whose teeth engage with a pinion, B, on a shaft, C'. Rigidly attached to this same shaft is a large gear-wheel, C, which engages with a small gear-wheel, D, and which latter meshes with gear-wheel E on crank-shaft E'. The outer

ends of this shaft are provided with cranks 50 G, while the middle of the shaft is provided with a balance-wheel, F. To the cranks G, on each side of the machine, are connected the chisel-bars H, which at their extreme lower ends are provided with sharp chisel-edges H'. These bars H slide through guides J, which are made to oscillate in a circular bearing in a plate, J'. The motion thus transmitted to the chisels, it will be seen, is an accelerated one.

S is a toothed wheel journaled at the front of the machine, which wheel runs upon the ice and supports the front end of the machine.

In operating my machine the crank-handle 65 P is rotated, and this serves through the gears O N M L to slowly propel the machine forward, and also through the gears A C D E serves to rotate the cranks G in the direction of the arrow, which causes the chisel-bars H to 70 have a compound reciproco-oscillatory motion, causing the said bar both to slide in the guide J and also to rock with the same, as about a fulcrum. The movement which the bar H makes is a downstroke for the rear half of 75 the crank-stroke and an upstroke for the front half of the crank-stroke, which gives to the chisel-point below the guide J a reversed or rearwardly-traveling sweep as it cuts down into the ice, as indicated by the 80 arrow, and which rearward sweep acts in harmony with the forward progression of the machine as it moves over the ice from its feed devices. With this machine, the feed-mechanism being arranged for a diminished 85 motion and the chisel mechanism for an accelerated motion, it will be seen that the rapid impact of blows delivered by the chisel upon the ice cuts a groove in the same, which permits of easy subdivision of the sheet of ice 90 into blocks of approved size.

Having thus described my invention, what I claim as new is—

The combination, with the main frame, of a drive-shaft, O', a train of diminishing gear-wheels, O N M L, shafts M' and K', and toothed feed-wheels K, fixed to shaft K', the train of speed-accelerating wheels A B C

D E, crank-shaft E', with cranks G and fly-wheel F, rods H, jointed to the cranks and provided with chisels H' at the lower ends, and rocking bearings J, embracing and guiding the chisel-rods, the said chisel-rods and gears being arranged to cause the chisels to move to the rear on the downstroke to co-

operate with the advance movement of the machine, substantially as described.

DANIEL WILLIAMSON.
